UNITED STATES PATENT OFFICE.

FREDERICK KOENIG, OF PITTSBURGH, PENNSYLVANIA.

UNDERFEED STOKER.

1,393,292.

Specification of Letters Patent. Patented Oct. 11, 1921.

Application filed December 19, 1918. Serial No. 267,480.

To all whom it may concern:

Be it known that I, FREDERICK KOENIG, a citizen of the Republic of Switzerland, residing at Pittsburgh, in the county of Allegheny, and State of Pennsylvania, have invented certain new and useful Improvements in Underfeed Stokers, of which the following is a specification.

My present invention relates in general to 10 underfeed stokers for locomotives; and has reference more particularly to improvements in the means of support for that type of furnace grate ordinarily used in connection with such underfeed structures. Heretofore, the raised edges or upper portions of 15 the fuel charging trough have been relied upon to marginally support the grates, but as these portions were subject to the destructive effect of the fire it has been found necessary to remove and replace them at 20 frequent intervals, practically every few weeks under normal conditions of service, and this replacement consequently necessitated the concurrent removal of the grates before such 25 replacement could be effected.

One of the principal objects of the invention, therefore, is to so organize the trough as to provide a support for the grates which is remote from the fire and its effects, and 30 which at the same time permits the upper raised edges of the trough to be readily removed and as easily replaced without in any way disturbing the grates. Other objects 35 of the invention in this connection relate to the provision on such raised edges of grate elements adapted to coöperate with corresponding elements of the grate, together with the mounting of the grate shafts in the aforesaid support; and the provision of a 40 sectional trough construction composed of removable parts, one of which is designed to coöperate with the grate bars and to be removed without disturbing the other part which serves as a support for the grate and 45 its shafts.

These, together with such other objects as may be hereinafter described, or are incident to my invention, I attain by means of a construction illustrated in preferred form in 50 the accompanying drawings, wherein—

Figure 1 represents a top plan view of a set of furnace grate sections and their charging troughs in which my invention is embodied; and

Fig. 2 is a view in vertical section thereof, taken along the line 2—2 of Fig. 1.

Referring to the drawings, the reference characters 3, 4, denote the inner and outer sheets, respectively, of the fire box A within which are mounted the fuel charging troughs 60 B. These troughs, of which two are here shown, serve, in conjunction with supplementary feed apparatus (not shown), to supply fuel toward and upon the grates C and D in the usual manner. As shown, these 65 grates include agitator shafts 5, and the sets of grate bar elements 6, 7 and 8, adapted to be rocked by the shaft when the latter receives actuation. The construction thus far described represents nothing but what is old 70 and well-known in this art; and in itself forms no distinct part of my present invention.

In carrying out my invention, each side wall of the troughs B, above its lower portion 9, preferably comprises the raised edge or upper portion 10 and a cast steel inner side piece 11 seated between the upper edge of the lower portion 9 and the shoulder 10' of the raised edge member 10. The lower 80 portion 9 and the upper portion 10 are provided with flanges 9^a and 10^a respectively, which abut the marginal back portions of the side piece 11, as shown in Fig. 2. This arrangement prevails throughout both 85 troughs, as will be understood, though of course, it is obvious that only one trough may be employed wherever such may be considered preferable.

The reference numerals 12 designate outer 90 side portions of a grate supporting structure which portions are provided at their ends with the bearing bars 13 and 13' having end bearings 14 for each of the grate shafts, and these portions 12 are centrally formed 95 with ribs 12^a which seat between the flanges 9^a and 10^a when the members 10, 11 and 12 are detachably brought together into association by means of the upper and lower series of headed bolts 15 and nuts 16, as in 100 the manner illustrated. In the case of the central grate D, each grate supporting structure proper will then, as indicated, comprise the side portions 12 having a bearing bar 13 at each end, while in the instance of either 105 side grate C, it will include the bearing members 13', a side portion 12, and a complementary side portion 12' mounted against the lower portion of the inside sheet 3 of the fire-box. The raised portions 10 and said 110 side portions 12' are provided with fixed grate elements 17 and 18 which respectively

coöperate with the movable grate members 6 and 7 already described.

To remove a raised member 10 when such removal becomes necessary by reason of the 5 disintegrating effect of the fire upon it, the upper row of bolts is uncoupled, whereupon the raised edge may be lifted out without disturbing the grate or the existing relation of the support with reference to the grate 10 and trough. In some cases it may be found necessary to slightly loosen the nuts of the lower row of bolts in order to more readily allow of such removal, but in any such event the supporting relation remains un- 15 disturbed since the rib 12^a of the side portion 12 would still rest upon the positioning portion or flange 9^a of the trough base. The entire arrangement of the various parts is therefore simple and efficient, and, fur- 20 thermore, extended bearing and supporting surfaces of coöoperating parts are provided for in a very ample manner. Obviously since the location of the grate supports is below and remote from the fire, their in- 25 tegrity is preserved, the proper positioning of the grate is at all times maintained, and the occasion for its removal reduced to a minimum.

What I claim is:

- 30 1. In an underfeed stoker, the combination with the grate, of an underfeed trough member therefor provided with a fixed lower portion and a detachable upper portion, and means for supporting the grate from the lower portion so as not to interfere with detachment of the upper portion.
2. In an underfeed stoker, the combination with a grate and its shaft, of an under- 35 feed trough member provided with a de- 40 detachable upper portion terminating in a

plane approximating that of the upper face of said grate, and having a lower portion provided with laterally extending grate supporting means constituting a bearing for said shaft.

45

3. In apparatus of the character de- 50 scribed, the combination of a grate and its shaft, a grate charging trough having a side wall thereof provided with a detachable upper edge portion and a detachable side portion, said side portion provided with laterally extending grate supporting mem- 55 bers positioned and formed to constitute bearings for the shaft of said grate, and de- 60 tachable clamping means for said portions.

55

4. In an underfeed stoker, the combina- 60 tion of a grate section having movable grate elements, and a trough for supplying fuel to said section having upper and lower side wall sections, said lower section constructed and arranged to support the grate section, and said upper section detachably connected with said lower section and provided with fixed grate elements coöperating with said movable grate elements.

65

5. In an underfeed stoker, the combina- 70 tion of a grate, a feed trough constructed to provide a means of support for said grate and having an upper edge portion disposed in contiguity with but removable independ- 75 ently of said grate.

6. In an underfeed stoker, the combina- 75 tion with a grate of a trough having a rela- tively fixed lower portion, a removable upper portion and means for supporting the grate from the lower portion in such manner as to permit removal of the upper portion without removal of the grate.

FREDERICK KOENIG.
